HOLDERS FOR SAFETY RAZOR BLADES

Reginald Edward Carter, Shirley, England

Application March 24, 1950, Serial No. 151,791

2 Claims. (Cl. 30—329)

This invention relates to holders for safety razor blades whereby to provide a cutting tool for many purposes, and more especially for small model making, dissecting, preparation of samples for microscopic examination and the like, requiring accuracy and precision. The invention is intended more especially (although not exclusively) for use with blades having only a single cutting edge, such as those known under the registered trade marks "valet," "Corrux," "Wilkinson," "Rolls" and the like.

The invention consists in a holder for a safety razor blade comprising a tube longitudinally slotted to receive one edge of the blade.

The invention will be clearly understood from the following description of one form (given, however, merely by way of example) which it may assume, and this description will be more readily followed by reference to the accompanying drawings wherein:

Figure 1 represents in perspective a razor blade holder, with cover guard, according to the invention; and

Figures 2a-2i represent the separated parts of the assembled tool shown in Figure 1.

In carrying the invention into effect in one convenient manner as shown in the drawings herewith a holder for a safety razor blade comprises a metal tube 1 of any suitable length the whole or part of which is longitudinally slotted, as at 2, and a portion of which has formed thereon a handle 3. The slot 2 may be somewhat longer than a blade 4 to be fitted therein. The tube may, if desired, be internally grooved opposite to the slot 2, as at 5, in order to form a seat for receiving the rear edge of the blade 4. The tube 1 is preferably of tempered spring steel or other resilient material, and the slot 2 is narrower than the thickness of blade 4. The corners of the slot and the end of the tube may be rounded as shown to facilitate insertion of the blade 4 which is forced into the slot, with the rear edge of the blade against the remote inner surface of the tube 1 (and in the groove 5, if provided). Owing to the narrowness of the slot 2, and the resilience of the tube 1, the blade is held firmly in this position by friction.

In order to facilitate removal of a blade from the slot 2 there is provided an ejector 6 (Figure 2i) in the form of a rod or tube of suitable diameter to slide into the tube 1 from the rear end. The ejector, after complete removal from the holder, may also be used as an ejector for loading a blade into the slotted end of the holder. One end of this ejector is forked, as at 7, allowing it to be inserted fully into the tube 1, even when a blade is held in slot 2, by ensuring that the two limbs of the fork 7 project, inside the tube 1, on opposite sides of the inserted blade. The opposite end of the ejector 6 has formed thereon a knob or shaped block 8 forming an end extension of the handle 3. The handle 3 and block 8 may conveniently be formed of a synthetic resin moulded on to the tube 1 and ejector 6 respectively. In cross section the handle 3 and block 8 are preferably substantially elliptical. As shown i. e. each has a longitudinal projecting side portion with convergent sides so that when a holder, with a blade fitted

therein, is rested lengthwise on a flat surface it cannot stand, without support, in a position with the blade erect, but will roll over until the cutting edge of the blade rests on the flat surface. To facilitate this rolling action and for convenience of grip the handle is enlarged, as shown towards its free extremity, on the same side of the handle axis as the blade slot (and any blade projecting therefrom) and the end surface of the block 8 may be curved and/or shaped off at an oblique angle in order to fit the palm of the user's hand.

In order to remove a blade from the slot 2 the ejector 6 is withdrawn rearwardly until the fork 7 is free of the inserted blade 4 inside the tube 1, and then rotated by a sufficient amount up to 90°, so that the fork 7 extends transversely of the blade. When the ejector is then forced inwards it drives the blade 4 almost completely out of the slotted tube 1, allowing it to be readily gripped between the operator's fingers and finally withdrawn. The ejector is then again rotated in reverse sense by a sufficient amount so that the fork 7 is aligned with the slot 2 (and groove 5 if provided) allowing another blade to be inserted.

For protection when the tool is not in use there is provided a cover guard 9 for the blade and the portion of the holder in which it is fitted. This guard is adapted to slide telescopically over the end of the tube 1 and is shaped also to cover the blade fitted therein, as seen in Figure 1. Means are provided to lock the guard in position, and it may be provided with a pocket clip, as shown, to allow it to be secured in a user's pocket.

One convenient construction of the guard will be understood by reference to Figures 2a-2f showing the separate parts thereof. A sleeve 10 (Figure 2e) is adapted to slide telescopically on to the tube 1 and is longitudinally slotted at 11. The cover proper (Figure 2d) is preferably of sheet metal folded, and joined by a channel strip secured to its folded edges, to form a key-hole cross-section, of which the cylindrical portion 12 is of suitable diameter to fit tightly and permanently upon the sleeve 10, with its longitudinal gap 13 in line with slot 11, while the projecting plate portions 14 are of suitable size and spacing to encase the projecting portion of a blade fitted into tube 1. The top edge of the portion 12 of the cover is aligned with the top edge of sleeve 10, which is of sufficient length to project below the cover portion 12 where there is mounted thereon a longitudinally slotted collar 15 (Figure 2f). The base of the sleeve 10 is flanged to hold on the collar 15 which is loose, and rotatable thereon.

It will be seen that since the slot 11 of sleeve 10 is in alignment with the gap 13 of the cover 12, the collar 15 can be rotated until its slot is in line with slot 11 and the whole cover assembly can then be fitted on to, and over, tube 1 and a blade fitted therein, to form a complete guard. In this position the collar 15 is below the blade, and can be rotated to close the bottom of slot 11.

To facilitate operation the outer surface of the collar 15 may be knurled as shown (Figure 2f): and to prevent accidental release of the lock one or more dimpled indentations 16 in the collar 15 may engage one or other of the like dimpled indentations in sleeve 10.

The top of the cover guard is preferably closed and for that purpose there may be provided a metal annulus 17 with a projecting lug 18 (Figure 2c). The annulus 17 is centrally screw threaded, and is of external diameter to fit into the top of sleeve 10. The undersurface of lug 18 is stepped round the edge to fit into and on the upper edges of the adjacent plate portions 14 of the cover. Three small equispaced lugs or abutments 19 are inturned at the top edge of sleeve 10, and the edge of annulus 17 is chamfered away at three corresponding points. The annulus 17 is inserted beneath the lugs 19, and the stepped lug 18 is fitted to the gap between plate portions 14

of the cover. A ring with downwardly projecting spring pocket clip 20, of conventional form, (Figure 2b), is positioned on the lugs 19 of sleeve 10 and a dome-headed (or other shape) screw 21 (Figure 2a) extending through this ring engages with the screw threaded aperture of annulus 17 thus gripping the annulus and ring together on opposite sides of the lugs 19, to hold the closure members of the cover guard firmly in position.

It should be understood that the invention is not limited solely to the details of the forms described above which may be modified in order to meet various conditions and requirements encountered without departing in any way from the scope of the invention as defined in the appendant claims.

What I claim is:

1. A holder for receiving a safety-razor blade to form a cutting tool comprising a spring-metal tube having, at one end and in one side only, a longitudinal slot extending for a short distance from the end of the tube, for receiving and gripping a safety-razor blade, and a blade-ejector in the form of a rod of circular cross-section of greater length than the unslotted length of said tube, adapted to be inserted telescopically into said tube and to be housed therein when a razor-blade is gripped in said slot, the inner end of said rod being forked to extend internally

4
into the slotted length of said tube and there to extend on opposite sides of a razor blade when gripped in said slot.

5 2. A holder for receiving a safety-razor blade to form a cutting tool as claimed in claim 1, including a handle formed on the unslotted length of said tube, said handle having a longitudinally projecting side portion with convergent sides, said projecting side portion being substantially in line with said razor blade when the latter is gripped in said slot.
